UNITED STATES PATENT OFFICE

ELMER L. SMITH, OF LONGMEADOW, MASSACHUSETTS, ASSIGNOR TO PACKAGE MACHINERY COMPANY, OF SPRINGFIELD, MASSACHUSETTS, A CORPORATION OF MASSACHUSETTS

AUTOMATIC FEED FOR WRAPPING MACHINES

Application filed May 15, 1930. Serial No. 452,682.

This invention relates to mechanism for feeding singly to a wrapping machine or other article treating devices a succession of articles such as cigars. Cigars are generally pressed in layers of fifteen or twenty-five and it is one object of this invention to permit these layers to be stacked manually in a magazine, fed from the magazine one layer at a time, and delivered to the wrapping machine in individual succession. A further object of the invention is to prevent any displacement of the cigars during their transit from the magazine to the point at which they are delivered to the wrapping mechanism. A further object is to feed the cigars individually in a downward direction into pockets in a revolving disk, the pockets having at least one slanting end so that the cigars are automatically located in the correct position. A further object of the invention is to stop the feeding of the cigars to the wrapping mechanism in the event that there is a break in the continuity with which the cigars are being fed from the magazine. A further object is to improve generally upon the type of cigar feeding mechanism illustrated and described in the application of Frederick Grover, filed May 12, 1930, Serial No. 451,688.

In accordance with these objects the invention consists generally in a magazine from which layers of cigars are forced bodily, one layer at a time, by a plunger. The cigars are received from the plunger upon an elevated table which descends after the delivery of a layer thereto, so that the layer of cigars is deposited upon a pair of parallel flat-backed chains, in this case composed of chains of the so-called silent type which have been found to be excellent for this purpose. The conveyer chains are continuously moving and the cigars are held out of contact with the conveyer until they have been delivered fully into position above it. A second chain similar to the first extends

above it so that the cigars are held against movement during their transit along the chains. At the end of the chains the cigars are delivered in single file to guide members along which they are fed by the pressure of the cigars behind them. Normally the leading cigar of the file strikes a stationary abutment and is then in position to be grasped by opposed plungers and carried into the pocket of the feeding disk of a cigar wrapping machine of the type shown in my prior application Serial No. 424,998, filed January 31, 1930. A stop mechanism is provided so that if the continuity of the single file of cigars is broken one of the opposed plungers will be held stationary in a position where it blocks further advance of the file of cigars and prevents any further delivery of cigars to the feeding disk until continuity is again restored.

Referring to the drawings:—

Fig. 1 is a side elevation of a cigar feeding machine embodying my invention;

Fig. 2 is a fragmentary section thereof illustrating the delivery end of the machine;

Fig. 3 is a top plan view of the machine;

Fig. 4 is a section on line 4—4 of Fig. 3;

Fig. 5 is a section on line 5—5 of Fig. 4;

Fig. 6 is a section on line 6—6 of Fig. 3; and

Fig. 7 is a section on line 7—7 of Fig. 4.

Figs. 8 and 9 represent detail views of a spring pressed plunger, article stop mechanism.

The description of the machine will start with the magazine in which the cigars are initially stacked by hand or by other suitable means. The machine is supported upon a frame 10 to which a magazine supporting bracket 11 is secured. A plate 12 carried upon this bracket forms the bottom of a cigar magazine, the ends of which are formed by upright pieces 13. The front plate 14 of the magazine is held in place at an adjustable elevation by screws 15.

passing through slots 16 in the front plate and into threaded holes in the uprights. The back 17 is made readily removable so that the cigars may be placed within the 5 magazine in orderly layers. To facilitate the loading of the magazine a rear bracket 18 is secured to the bracket 11 and carries on its top a loading table 19. This table as well as the rear upright members are preferable made adjustable to accommodate cigars of different dimensions.

To force the bottom layer of cigars out of the space between the plate 12 and the bottom of the front plate 14 a reciprocating 15 plunger is provided. Upon supports 20 extending from the bracket 11 are ways 21 in which run rack slides 22 carrying a pusher carriage 23. A pusher plate 24 provided with a head 25 is secured to this carriage. 20 To slide the carriage back and forth in the ways the rack slides 22 are provided with teeth 26 meshing with pinions 27 fast upon a shaft 28 which is journaled in bearings 29. A pinion 30 upon this shaft meshes 25 with a rack 31 held in position by a guide 32 and pivoted at 33 to the end of a crank member 34 swung at 35 upon the frame. The crank is formed with a slideway 36 in which reciprocates a block 37 pivotally mounted upon a disk 38 secured to a shaft 39. At the other end of this shaft is a worm wheel 40 meshing with a worm 41 upon a cross shaft 42 which, in my preferred embodiment of the machine, is driven in any 35 suitable manner from the cooperating wrapping machine so that it rotates in timed relation therewith.

As the cigars are fed from the magazine by the plunger they are prevented from 40 over-travel by an abutment 43 formed on the frame. In this position the cigars are received upon table members 44 carried upon brackets 45 pivotally mounted at 46 (Fig. 5) to similar arms of a pair of identical bell cranks 47 mounted on rock shafts 48. The other arms of these bell cranks are joined by a link 49 so that they move in unison and provide a parallel motion for the table members 44. One of the shafts 48 has fixed to it an arm 50 (Fig. 1) provided at its end with a roll coacting with a crown cam 51 secured to the shaft 39. The plates are thus caused to move in timed 45 relation with the plunger which forces the layers of cigars from the magazine, and the cam 51 is so designed that the plates will remain in their elevated position during the entire outward movement of the plunger and will then descend to drop the layer of 55 cigars upon the chain conveyer.

A pair of chains 55 having their upper run passing over a plate 56 to preserve accurate alignment pass at one end around sprockets 57 secured on a shaft 58. This 60 shaft is carried in brackets 59 adjustably

mounted on studs 60 projecting from the frame, by means of lock nuts 61. At their other ends the chains pass around sprockets 62 (Fig. 2) secured to a shaft 63 which is geared at 64 (Fig. 3) to the cross shaft 42 previously mentioned. These chains are given a continuous movement at a relatively low speed so that the cigars will be fed as fast as is required for delivery to the wrapping machine.

In order to prevent the cigars turning or becoming displaced while they are on the chains, an upper chain 65 is preferably provided, positioned above and between the two lower chains. At one end this chain passes around a sprocket 66 (Fig. 1) secured to a shaft 67. A second sprocket 68 on this shaft is joined by a chain 69 with a sprocket 70 on the cross shaft 42. The sprocket sizes are so chosen that the upper chain moves at the same surface speed as the two lower chains. A tension roll 71 of the usual form is provided to maintain the chain 69 in proper condition. The upper run of the chain 65 passes over a support plate 72 suitably mounted upon the frame, in order to prevent it from coming in contact with other parts; and at the other end the chain passes around a sprocket 73 mounted upon an idle shaft 74. Both the upper chain and the two lower chains are preferably made of the silent construction common in power drives; although this form of chain is utilized here primarily neither for its power transmission nor its silent qualities, but because the back of the chain is substantially flat and thus supports the cigars without the necessity of providing special backs for the links of the chain.

At the delivery end of the chains the 105 cigars pass as shown in Fig. 2 onto a bottom support 75 and under a top plate 76, the cigars being forced onwardly by the pressure of the cigars behind them until they strike a stop plate 77. The foremost cigar of the file is thus held directly under an upper plunger 78 (shown depressed in Fig. 2), adjustably secured by a bolt 79 upon a plunger carrier 80. This carrier is pivoted at 81 to a lever 82 fast upon a rock shaft 83. The carrier is also pivoted at 84 to a link 85 extending from a fixed pivot 86 to provide a parallel motion. An arm 87 extends from the rock shaft 83 and carries at its end a roll coacting with a disk cam 88 mounted upon the cross shaft 42. A second arm 89 (Fig. 1) projects from the rock shaft and is joined by a spring 90 with a fixed part of the machine in order to hold the cam roll normally against the periphery 120 of the cam.

Cooperating with the upper plunger is a lower plunger 91 having upon its upper surface spring pressed pads 92 so that the cigars may be grasped between the two plungers 130

without injury irrespective of minor variations in size. The lower plunger is carried upon the end of a lever 93 pivoted at 94 to the frame and having a roll 95 cooperating with a cam (not shown in the drawings) upon the shaft 42. A spring, which has also been omitted from the drawings, may be provided to hold the roll in contact with the cam in the usual manner.

10 The present machine has been designed for use with a cigar wrapping machine preferably of the type shown in my prior application No. 424,998. Only a fragment of this machine has been shown as it is unnecessary to an understanding of my present invention. The frame of the machine is indicated at 96 and is joined to the frame 10 by a dowel or shaft 97. Intermittently rotating upon the wrapping machine frame is a 15 disk 98 having pockets 99 spaced about its periphery and corresponding in shape with a cigar. The frame 96 is provided with an aperture 100 with which the pockets 99 in the disk register successively as the disk is 20 moved with a step-by-step motion.

It is desirable to insure accurate centering of the cigars before they come into the range of the upper and lower plungers, as a longitudinal displacement of a cigar would 25 disturb its proper alignment with the pocket of the wrapping machine. For this purpose I have provided centering plates 101 (Fig. 3), one at either side of the channel formed between the plates 75 and 76. Each plate is 30 adjustably secured as at 102 to an arm 103 pivoted at 104 to the frame and having an adjustable stop 105 to limit the motion of the plates toward each other. A spring 106 constantly urges the plates toward each 35 other so that they always tend, unless otherwise restrained, to rest with their stops 105 against the fixed abutments on the frame. In order to give to the centering plates a periodical movement with a minimum of 40 working parts I prefer to bend the right-hand end of the arms 103, as viewed in Fig. 3, inwardly, and to provide rollers 107, one on the arm 89 and the other on the arm 87, so that at each actuation of the upper plunger 45 the centering plates will be moved temporarily away from each other and then returned under the influence of the springs so as to center accurately the cigars which are 50 located between them.

55 I also prefer to provide mechanism by which the feeding of cigars to the disk 98 will be prevented except when the file of cigars being fed by the conveyers is unbroken. For this purpose an arm 108 (Fig. 60 2) is rigidly secured to the shaft 83 which actuates the upper plunger and is provided with a notched plate 109. Cooperating with the notch in this plate is a blade 110 pivotally mounted upon a rock shaft 111. Also 65 secured to this rock shaft are feelers 112,

one extending at each side of the path of the conveyers 55 as shown in Fig. 3. A stop arm 114 (Fig. 1) extends from the rock shaft and normally abuts a stop 115 on the frame, the rock shaft with its attached parts being held yieldably in this position by a spring 113. As long as cigars are continuously passing along the conveyers the feeler 112 will be held in the dotted line position of Fig. 2. In this position the blade 110 does not interfere with the free motion of the shaft 83. If, however, there is a break in the continuity of the file of cigars the feeler will be allowed to snap into the full line position. In this case the blade 110 is directly opposite the notch in plate 109. As the roller on the end of arm 87 passes off the high point of cam 88 the upper plunger 78 would normally tend to rise under the influence of the spring 90. Such motion is, however, prevented by the contact of the blade 110 with the notched plate 109. The parts are so proportioned, however, that upon the next rotation of the cam the plate 109 will be moved from the blade a sufficient distance to permit the blade to snap away if a cigar has in the meantime arrived underneath the feeler 112. It will be noted that the upper plunger remains in its lowermost position whenever the feeler is held in the full line position. The feeding by the plunger of those cigars which had already passed the stop mechanism is thus prevented and a continuous file of cigars is assured at all times when the feeding mechanism is operating. It is preferred that the wrapping machine also shall have a stop mechanism so that if no cigar is delivered into the pockets 99 no wrapping material will be fed and thus waste will be prevented.

As previously mentioned, the machine is designed for use of cigars of different diameters and the magazine is made adjustable for this reason. A further capacity for change is also provided for, so that the machine may accommodate either alternate layers of twelve and thirteen or regular layers of twenty-five cigars. For this purpose the frame 10 is split at 116 and 117. If it is desired to add a magazine of different width the frame extending to the right in Fig. 1 beyond the split 116 can be removed, a longer chain 55 substituted and the enlargement accommodated by the mere substitution of a wider plunger plate 24 and the wider magazine. It may also be desirable to operate the machine without a magazine, the cigars being fed either by hand or directly from a banding machine. In this case the frame may be taken apart along the line 117, a shorter chain substituted, and the bracket holding the shaft 58 bolted in place along the line 117.

It is also preferred to provide the pockets 99 in the disk 98 with one bevel side 120

(Fig. 6) so that the cigars when placed within the pocket will always be forced toward the straight end of the pocket, irrespective of minor differences in cigar lengths. The bottoms of the pocket are generally open but are provided with short ledges 121 at the sides upon which the ends of the cigar may rest without, however, interfering with the operation of the upper and lower plungers.

In order to prevent any possibility of the cigars rolling over as they are presented to the plunger 78, I may use the modified mechanical construction shown in Figs. 8 and 9. The fixed abutment 77 has in this instance been replaced by a plate 130 carried on a rod 131 adjustably held by a set screw 132 in a fixed bracket 133. Pivoted at 134 to this bracket is an arm 135 having a projecting finger portion 136 extending through slots in both the plate 130 and the upper plunger 78 to contact with the leading cigar of the file. The finger is constantly urged towards the cigars by a spring 137 strained between the bracket 133 and an arm 138 secured to the arm 135. The tension exerted by the spring is sufficient to hold the leading cigar from rolling over, but not enough to prevent it from being pushed ahead by the pressure of the file behind it.

What I claim is:

1. A feeding device for cigars or similar articles which comprises a pair of endless conveyers, one positioned above the other to form between them a feeding channel for a file of articles, a stop against which the articles are delivered by the conveyers, a pair of centering plates adapted to center the articles as they approach the stop, mechanism to separate the plates periodically to free the articles between them and to bring the plates towards each other to cause them to center the articles between them, and a pair of plungers operative to grasp between them the leading article abutting the stop and carry said article out of its position in the file.

2. A feeding device for cigars or similar articles which comprises means for delivering articles in single file, a plunger operative to feed the articles successively out of said file, and means responsive to an interruption in the continuity of the file for holding the plunger inactive and in position to block further movement of the file of articles.

3. A feeding device for cigars or similar articles comprising an intermittently rotatable disk provided with through pockets, each pocket having one beveled end and one straight end and ledges for holding a cigar therein, and means for depositing cigars singly and successively in the top of said pockets whereby the cigars will be positioned automatically in the pockets against the straight end thereof irrespective of

minor variations in the lengths of the cigars.

4. A feeding device for cigars or similar articles comprising an intermittently rotatable disk provided with through pockets, each pocket having one beveled end and one straight end and ledges for holding a cigar therein, means for delivering cigars successively to a point immediately above that at which the disk pockets come to rest, and a pair of plungers coordinated to grasp the cigars and lower them into the pockets, the lower of the plungers being narrower than the space between the pocket ledges so that it may pass through each pocket in succession.

5. A feeding device as claimed in claim 4, having movable members for aligning the cigars as they are delivered into position to be grasped by the plungers, and mechanism operated by the plungers for moving the members towards and from each other.

6. A feeding device for cigars or similar articles which comprises a pair of endless conveyers, one positioned above the other to form between them a feeding channel for a file of articles, a stationary stop positioned beyond the conveyers against which the articles are delivered by the pressure of the articles being fed forward by the conveyers, a spring pressed plunger adapted to receive an article prior to its contact with the stop and to ease it into such contact without permitting it to roll over, and means for removing the article from its position against the stop.

In testimony whereof I have affixed my signature.

ELMER L. SMITH.
